RAILWAY CAR TRUCK

James A. Shafer, East Cleveland, Ohio, assignor
to National Malleable and Steel Castings Com-
pany, Cleveland, Ohio, a corporation of Ohio

Application June 24, 1931, Serial No. 546,488

14 Claims. (Cl. 105—220)

This invention relates to railway car trucks and more particularly to the journal boxes and side frames thereof. The invention provides an improved side frame and journal box construction 5 wherein the parts are maintained effectively in assembled relation and at the same time removal of the side frame may be accomplished with marked facility. Through my invention the side frame is freed for withdrawal merely by raising 10 of the bolster and it is unnecessary to raise the side frame to effect its removal. A further feature of the invention resides in provision for the minimizing of thrusts between the journal box and the journal in response to outward thrusts 15 of the side frame. Other features of the invention will be hereinafter described and claimed.

In the accompanying drawings:

Fig. 1 is a side elevational view with portions broken away, of a car truck embodying my invention.

Fig. 2 is an enlarged plan view showing an end portion of the side frame and its relation to the associated journal box.

Fig. 3 is a longitudinal vertical sectional view 25 on line III—III of Fig. 2, and

Fig. 4 is a transverse vertical sectional view on line IV—IV of Fig. 3.

Referring to the drawings there is shown a side frame 5 provided with a window 6 for the 30 reception of an end of the bolster 7. At its opposite ends the side frame engages the journal boxes 8, 8 as hereinafter specifically described. It will, of course, be understood that a similar side frame is provided on the other side of the car truck for 35 receiving the opposite end of the bolster 7 and cooperating with journal boxes on said other side in the same way as the side frame 5. However, a consideration of but one of the side frames and the parts associated therewith is sufficient for 40 an understanding of my invention.

The side frame 5 is of the type shown in my pending application Serial No. 459,480, filed June 6, 1930, having below the window opening 6 a portion designated generally by the numeral 9, 45 in which springs 10, 11 arranged longitudinally of the side frame are adapted to be seated and housed. Said portion 9 comprises a bottom shelf 12, a top flange or shelf 13, and side walls connecting said bottom and top shelves, said side 50 walls merging into the side walls of the channel shaped tension members 14 of the side frame. The bolster 7 is provided with lugs 15 which extend downwardly through openings 16 in the shelf 13 and rest upon spring caps 17 on the respective springs 10, 11. Also, the end of the bol-

ster extending into the opening 6 is hollow and receives a pair of springs arranged longitudinally of the bolster and resting upon the top of the shelf 13, one of said springs being shown at 18 in Fig. 1. The bolster is thus supported both by the springs 10, 11 below the shelf 13 and by the springs above said shelf. The above described relationship between bolster, the bolster supporting springs, and the side frame is the same as in my pending application above identified.

I provide the side frame 5 at each end thereof, with a pair of transverse grooves 19, 20 for receiving corresponding ribs 21, 22 extending from the associated journal box. The grooves 20 are shown provided in ears 23 projecting from the tension members 14 of the side frame. The rib 21 on each journal box is shown positioned on the upper corner thereof furthest from the side frame opening 6, while the rib 22 projects from 20 the side of the journal box adjacent the ear 23 on the associated tension member 14. Clearance is provided, as shown, between each of the ribs 21, 22 and the surfaces of the respective grooves 19, 20, cooperating therewith, and in addition 25 said ribs are curved transversely of the side frame (as indicated at 21' and 22' in Figs. 2 and 3, the cooperating groove surfaces being indicated at 19', 20') to provide for lateral angling between the journal box and the side frame.

The journal boxes are shown as of the roller bearing type disclosed in the pending application of Albert O. Buckius, Serial No. 332,346, filed January 14, 1929. Thus each journal box comprises a housing 8 having a continuous inner cylindrical surface 25 forming a race for roller bearings 26, two sets of which are shown. A cylindrical member 27 surrounding the axle or journal 30 forms an inner race for the roller bearings. Cages or retaining rings 29 for said bearings are 40 shown positioned between the inner and outer races referred to. Surrounding the axle 28 and secured to the housing 8 is a plate 30 forming the rear portion of the journal box. In the bottom portion of the housing there is provided an oil reservoir 31. A thrust block 32, preferably of bronze or similar material, cooperates with the front portion of the journal box housing; said block cooperating with the outer cage members 29 to assist in holding the roller bearings in 45 place. The housing 8 is counterbored at 33 to receive the flange 34 of the thrust block. At its outer face 35 said thrust block bears against the inner face of the cover plate 36, while the inner face 37 of said block is adapted to bear against 50

the end face 38 of the axle for transmitting thrusts thereto. Block 32 also has a semi-circular projection 39 adapted to seat in a recess 40 behind the annular shoulder or flange 41 on the 5 end of the axle. The cover 36 may be removably secured to the housing 8 by bolts 42. Extending through a staple 43 on the inside of the cover 36 is a lubricating wick 44, which projects into a slot or central recess in the thrust block. The 10 cover 36 is also provided with a recess 45 surrounding the top and sides of the wick and maintaining the latter in its proper relation to the cover. These various features involved in the 15 internal construction of the journal box are fully disclosed in the Buckius application above specified.

Each of the journal boxes is provided at the top thereof with a recess 46 for the reception of the wear plate 47 upon which the adjacent end of the 20 side frame rests. The wear plate 47 is crowned transversely, as at 48, to provide for a rocking bearing for the side frame. Projecting upwardly from the wear plate 47 is a lug 49 cooperating with the inner side of the adjacent end portion 25 of the side frame to provide a thrust bearing therefor. The thrust bearing surface 50 of said lug is curved as indicated in Fig. 2. I provide such thrust lug at the inner side only of the side frame, the portions of the wear plate 47 and of the journal box that extend outwardly of said 30 side frame presenting no lug or projection opposing outward movement of the frame. Outward movement of the side frame with respect to the bolster and to the opposite side frame of the truck is of course restricted by the engagement of the bolster lugs 15. The arrangement above described, wherein the only thrust projection on the journal box for engagement with the side frame is at the inner side of the latter, reduces to a minimum the thrust between the 35 respective flanges 39, 41 of the thrust block 32 and journal 28 when the car body shifts laterally, as in rounding curves. Such lateral shifting of the car body, of course, carries with it the 40 bolster and the side frames engaged therewith. It will be seen that the thrust on the end flange 39 of the thrust bearing 32 in response to outward shifting of the journal box with the side frame is limited to an amount corresponding to 45 the frictional resistance between the side frame and the journal box. In other words, when the side frame moves outwardly and, due to the frictional engagement between said side frame and the journal box, the flange 39 of the journal box thrust lug 32 is brought into engagement with the annular flange 41 of the axle 28, the side frame is free to move further outwardly over the journal box and no greater thrust occurs 50 between said flanges 39 and 41 than is commensurate with the friction between the journal box and the side frame. This thrust, it will be apparent, is decidedly less than would occur between said flanges if the side frame were restricted from outward movement by an outer lug on 55 the wear plate 47 or other portion of the journal box. During lateral shifting of the car body and movement of one of the side frames outwardly; i. e., away from the inner thrust lugs 49 on its associated journal boxes, the opposite side frame is, of course, engaging the inner thrust lugs 49 on its cooperating journal boxes, so that the major portion of the thrust occasioned by said lateral movement of the car body is taken up by 60 the ends of the axles in the journal boxes engaged by said opposite side frame; and no more 65

than a minor portion of the thrust is taken up by the flanges 39 of the journal boxes engaged by the first mentioned side frame, there being, as above pointed out, no thrust lugs exterior of the side frame on the journal boxes.

Brake hangers 51 are provided on the side frame for connection in the usual way to the customary brake rigging (not shown).

When it is desired to remove either one of the side frames of my improved truck, it is merely necessary after disconnecting the brake rigging from the hangers 51, to raise the bolster sufficiently to disengage the projections 15 from the openings 16, wherupon the side frame may be readily withdrawn by simply moving the same outwardly over the associated journal boxes. Removal of the side frame may thus be effected without raising the side frame, as is necessary in arrangements where thrust lugs exterior of the side frame are provided on the journal boxes.

It will be noted that (as in my above-specified pending application No. 459,480, as well as in my application Serial No. 347,262, filed March 15, 1929) the shelf 13 of the side frame, through which the bolster lugs 15 extend, is substantially in the horizontal plane that passes through the centers of the journals in the journal boxes 8. Thrusts of the bolster laterally of the side frame are imparted to the latter both through the engagement of portions 7' of the bolster with the 30 side frame columns 6' at the sides of the window opening 6 and through the engagement of the lugs 15 with the side frame shelf portion 13. Similarly, longitudinal thrusts are applied by the bolster to the side frame through engagement with the 35 columns and with the shelf 13. Due to the division of bolster thrusts between the columns 6' and shelf 13 there is a reduction of the stresses applied to the columns whether from lateral thrusts of the bolster as in rounding curves or from longitudinal thrusts as when the brakes are applied. It should further be noted that in my present invention the journal box ribs 22 and the cooperating side frame grooves 20 are positioned substantially in the aforesaid horizontal plane passing through the centers of the journals. Through 40 this arrangement it will be apparent that the forces tending to rotate the journal boxes upon application of the brakes are reduced to a minimum, as are also the stresses in the neighborhood of said boxes. In addition, the location of the lugs or ribs 22 and grooves 20 substantially in the horizontal plane passing through the centers of the journals results in a connection between the journal box and side frame which connection is of maximum effectiveness and at the same time enables wheel changes to be accomplished readily and expeditiously. It may be noted that if the lug 22 were nearer the top of the journal box, the latter would have more of a tendency to 50 rotate said lug out of engagement with the recess 20; whereas if said lug were moved below the position shown, it would be necessary to extend said lug and the cooperating member 23, due to the sloping of the tension member 14, with 55 resultant increase in the weight of the parts. With the lugs and grooves aforesaid in the position shown in quick wheel change connection of maximum strength and efficiency is provided.

Matter shown and described but not claimed herein is claimed in my applications hereinbefore mentioned.

The terms and expressions which I have employed are used as terms of description and not of limitation, and I have no intention, in the use 75

of such terms and expressions, of excluding any equivalents of the features shown and described or portions thereof, but recognize that various modifications are possible within the scope of the invention claimed.

I claim:

1. In a car truck, a side frame, a bolster, inter-engaging means therebetween comprising a projection on one of said members extending into an opening in the other, journal boxes slidably engaged by the respective ends of said side frame, each of said journal boxes providing for unobstructed outward movement of said side frame thereover and having a thrust projection engageable by the inner side of said frame, said journal boxes and side frame being further so constructed and arranged as to enable vertical and lateral angling to take place therebetween. 10
2. In a car truck, a side frame, a journal box slidably engaged by an end of said side frame, said journal box having on the inside thereof a thrust element and the associated journal having an end flange positioned outwardly of said element and engageable thereby for receiving outward thrusts of said box on its exterior providing for unobstructed outward movement of the side frame with respect to said box and having on its exterior a thrust projection engageable by the inner side of said side frame. 20
3. In a car truck, a side frame, a journal box slidably engaged by an end of said side frame, said journal box having on the inside thereof a thrust element and the associated journal having an end flange positioned outwardly of said element and engageable thereby for receiving outward thrusts of said box on its exterior providing for unobstructed outward movement of the side frame with respect to said box and having on its exterior a thrust projection engageable by the inner side of said side frame, the end of said journal in said box cooperating with a portion of said box for receiving thrusts imparted by the side frame to the box through engagement with said projection. 30
4. In a car truck, a journal box, a side frame slidably engaging said box, said box having on the inside thereof a thrust block, a portion of which is adapted to engage the end of the associated journal for transmitting thrusts thereto in one direction, said block having a flange and the journal having a cooperating flange engageable thereby for receiving thrusts in the opposite direction, said box on its exterior providing for unobstructed movement of the side frame outwardly of said box and having on its exterior a thrust projection engageable by the inner side of said side frame. 40
5. In a car truck, a journal box receiving a journal therein, a side frame slidably engaging said box, roller bearings between said box and said journal, a thrust block within said box cooperating with said bearings for maintaining the same in position and having a portion adapted to engage the end of the associated journal for transmitting thrusts thereto in one direction, said block having a flange and the journal having a cooperating flange engageable thereby for receiving thrusts in the opposite direction, said box on its exterior providing for unobstructed movement of the side frame outwardly of said box and having on its exterior a thrust projection engageable by the inner side of said side frame. 50
6. In a car truck, a side frame, a bolster engaged therewith, journal boxes upon which the ends of said side frame are slidably mounted, engaging means between said bolster and side frame arranged to provide for disconnection of the side frame from the bolster by raising of the latter, the portions of said journal boxes cooperating with the side frame providing for unobstructed outward movement of the side frame enabling the latter to be removed following raising of the bolster without requiring raising of the side frame. 60
7. In a car truck, a side frame including a tension element, a journal box upon which one end of said side frame is mounted, a connection between an upper corner of said journal box and the end of said side frame and comprising a groove in one of said members and a rib on the other received in said groove, and a rib and groove connection between a side of said journal box and said tension element, said rib and groove connections being so constructed and arranged as to enable lateral and vertical angling to take place between said journal box and said side frame. 10
8. In a car truck, a side frame including a tension element, a journal box upon which one end of said side frame is mounted, a connection between an upper corner of said journal box and the end of said side frame and comprising a groove in one of said members and a rib on the other received in said groove, a rib and groove connection between a side of said journal box and said tension element, the journal box on its top providing for unobstructed outward movement of the side frame with respect to the journal box and having on said top a thrust projection engageable by the inner side of said side frame. 20
9. In a car truck, a side frame including a tension element, a journal box upon which one end of said side frame is mounted, a connection between an upper corner of said journal box and the end of said side frame, and a connection between a side of said journal box and said tension element, said connections being constructed and arranged to provide for unobstructed transverse movement of the side frame over the journal box into assembled relation thereto while the journal box is assembled with its axle, and to provide for vertical and lateral angling between said journal box and said side frame. 30
10. In a car truck, a side frame including a tension element, a journal box having a journal therein, one end of said side frame being mounted on said journal box, a connection between said tension member and said journal box, said side frame having a shelf portion provided with an opening, a bolster having a projection extending into said opening, said side frame shelf and said connection between the journal box and tension member being substantially in a horizontal plane passing through the center of said journal. 40
11. In a car truck, a side frame including a tension element, said side frame having a shelf portion provided with an opening, a bolster having a projection extending into said opening, a journal box for receiving the journal of a wheel of said truck, one end of said side frame being mounted on said journal box, and a quick wheel change connection between said journal box and the tension element of said side frame and comprising a projection on one of said members in slidably engagement with a groove on the other, said side frame shelf and said connection being substantially in a horizontal plane passing through the center of said journal. 50
12. In a car truck, a side frame including a tension element, a journal box for receiving the journal of a wheel of said truck, one end of said 60
- 70
- 75

side frame being mounted on said journal box, and a quick wheel change connection between said journal box and the tension element of said side frame and comprising a projection on one of 5 said members in slidable engagement in a horizontal plane with a groove on the other, said connection being substantially in a horizontal plane passing through the center of said journal.

13. In a car truck, a side frame including a 10 tension element, a journal box upon which one end of said side frame is mounted, a laterally slidable connection between an upper corner of said journal box and the end of said side frame, and a laterally slidable connection between a 15 side of said journal box and said tension element, the last mentioned connection being substan-

tially in a horizontal plane passing through the center of a journal in said box.

14. In a car truck, a side frame including a 5 tension element, a journal box upon which one end of said side frame is mounted, a connection between an upper corner of said journal box and the end of said side frame, and a rib and groove connection between a side of said journal box and said tension element, said connections being constructed and arranged to provide for assembling 10 said side frame and journal box by a movement of the side frame transversely of the journal box, while the journal box is assembled with its axle, and to provide for relative vertical and lateral angling between said side frame and said journal 15 box.

JAMES A. SHAFER.
